Primary Examiner — Patricia Palasik(74) *Attorney, Agent, or Firm* — Oblon, Spivak, McClelland, Maier & Neustadt, L.L.P.(57) **CLAIM**

The ornamental design for a liner for plasma processing apparatus, as shown and described.

DESCRIPTION

FIG. 1 is a front view of a liner for plasma processing apparatus showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a sectional view taken along line 7-7 of FIG. 1 thereof;

FIG. 8 is a sectional view taken along line 8-8 of FIG. 1 thereof; and,

FIG. 9 is a perspective view thereof.
